LET-OFF MECHANISM FOR LOOMS.

APPLICATION FILED MAY 18, 1903.

NO MODEL.

UNITED STATES PATENT OFFICE.

HENRY TOMLINSON AND JAMES J. MULDOWNEY, OF LAWRENCE, MASSACHUSETTS, ASSIGNORS TO DRAPER COMPANY, OF HOPEDALE, MASSACHUSETTS, A CORPORATION OF MAINE.

LET-OFF MECHANISM FOR LOOMS.

SPECIFICATION forming part of Letters Patent No. 747,273, dated December 15, 1903.

Application filed May 18, 1903. Serial No. 157,617. (No model.)

To all whom it may concern:

Be it known that we, HENRY TOMLINSON and JAMES J. MULDOWNEY, citizens of the United States, and residents of Lawrence, 5 county of Essex, State of Massachusetts, have invented an Improvement in Let-Off Mechanism for Looms, of which the following description, in connection with the accompanying drawings, is a specification, like characters on the drawings representing like parts.

This invention relates more particularly to let-off mechanism for looms of the type wherein in the warp-beam is positively rotated to gradually let off the warp as the weaving progresses, looms of this type being shown in United States Patents Nos. 618,363 and 436,724. Both patents show the well-known "Bartlett" let-off mechanism, wherein the tension of the warp depends upon the tension 15 of a spring, which is compressed when the warp depresses the whip roll or bar. The greater the tension of this spring the less will a given impulse of the warp compress it, and a correspondingly less motion will be given 20 to the let-off. It is easier to ascertain when the loom is running whether the warp is subjected to the desired tension and it is desirable to be able to adjust or change the tension while the loom is running, because it is 25 then easier to ascertain by the "feel" of the warp just what degree of tension is necessary. Heretofore it has not been possible in let-off mechanism of the type referred to to effect this adjustment when the loom is in 30 operation nor to effect a very exact adjustment when the loom is at rest without the exercise of considerable care and expenditure of time.

Our present invention in let-off mechanism 35 has for its object the production of simple and effective means for quickly, readily, and accurately adjusting or changing while the loom is in motion the tension of the spring which governs the tension and let-off of the 40 warp.

The novel features of our invention will be described in the subjoined specification and particularly pointed out in the following claims.

50 Figure 1 is a partial side elevation of a

loom provided with let-off mechanism embodying one practical form of our invention; and Fig. 2 is a transverse sectional detail, to be referred to, on the line 2 2, Fig. 1, looking toward the right.

We have illustrated our invention in connection with the Bartlett type of let-off mechanism, which includes a rocking carrier a' for the whip roll or bar W , attached to a rock-shaft a , provided with a depending 55 rocker-arm a^2 , the bent rod b longitudinally movable in a fixed guide b^x on the loom side A and pivotally connected at one end with the rocker-arm a^2 and the springs s and s^x on the bent rod, the latter spring being held between an adjustable collar b' on the rod and the perforated end of a lever c . A link c' connects the lever with the pawl-carrier f , having a pawl g to coöperate with the ratchet e , attached to the upright actuating-shaft d^x , 60 provided with a worm d , which through suitable gearing transmits rotative movement to the warp-beam B , all in well-known manner, a collar c^2 on the link being engaged by the actuator-rod c^3 , connected with and operated 65 by a moving part of the loom, as the lay-sword A^x , Fig. 1.

Heretofore the tension of the controlling-spring s has been adjusted by moving a collar in one direction or the other on the tension-rod b and holding it in adjusted position by a set-screw, and manifestly it is practically impossible to thus adjust the spring tension when the loom is in motion, and it is difficult to get the desired tension when the 70 loom is at rest.

We have made the adjusting-collar or abutment slidable on the tension-rod, and by simple means the collar can be moved with ease and great exactness to adjust the spring tension, whether the loom is in motion or at rest.

Referring to the drawings, the coupling m^x between the tension-rod b and the rocker-arm a^2 is shown as having an upturned pin m , longitudinally slotted at 10 to loosely receive a headed pin or stud a^4 on the rocker-arm, the coupling being apertured to receive the end of the tension-rod, which latter is held in place by set-screws 4.

The body of the coupling is provided with 90

depending transverse ears m' , apertured to receive loosely a controller, shown as a rod n^x , provided at its outer end with a hand-wheel n or other similar device and threaded at its inner end at n' , the controller being carried by the coupling in parallelism with the tension and held from longitudinal movement in the coupling by a collar n^2 between the ears and secured by a screw 6 to the rod n^x .

A block or abutment p is slidably mounted on the tension-rod b and engages the adjacent end of spring s , said block or abutment having a depending extension p' , provided with a screw-threaded hole p^2 , through which the threaded end n' of the controller extends. By rotating the latter in one or the other direction the abutment p will be slid forward or back on the tension-rod b to increase or decrease the tension of spring s , as may be desired, such adjustment of the tension being regulated with great exactness and nicely and with perfect ease, whether the loom is in motion or at rest.

Our invention is not restricted to the precise construction and arrangement herein shown and described nor to the precise form of let-off mechanism herein illustrated, as changes or modifications may be made by those skilled in the art without departing from the spirit and scope of our invention.

Having fully described our invention, what we desire to claim and secure by Letters Patent is—

1. In let-off mechanism for looms, a rocking carrier for the whip-roll, having an attached rocker-arm, a rod operatively connected therewith, a fixed guide through which said rod is movable longitudinally, an abutment movable on the rod, a tension-controlling spring interposed between the guide and the abutment, and manually-operated means to move the latter toward and from the guide while the loom is in operation and retain the abutment in adjusted position, to regulate the tension of the spring.

2. In let-off mechanism for looms, a rocking carrier for the whip-roll, having an attached rocker-arm, a rod operatively connected therewith, a fixed guide through which the rod slides, a slidable abutment on the rod, a tension-controlling spring encircling the latter between the abutment and guide, and manually-operated means mounted on the said rod and movable relative thereto to move the abutment toward and from the guide and hold it in adjusted position on the rod.

3. In let-off mechanism for looms, a rocking carrier for the whip-roll, having an attached rocker-arm, a rod operatively connected

therewith, a fixed guide through which said rod is movable longitudinally, an abutment slideable on the rod, a tension-controlling spring surrounding the rod between the guide and the abutment, and a rotatable controller carried by the rod and in operative engagement with the abutment, rotation of the controller moving the abutment toward or from the guide to regulate the tension of the spring while the loom is in operation.

4. In let-off mechanism for looms, a rocking carrier for the whip-roll, having an attached rocker-arm, a rod operatively connected therewith, a fixed guide through which the rod slides, a slidable abutment on the rod, a tension-controlling spring encircling the latter between the abutment and guide, a rotatable, threaded controller in engagement with the abutment, and means on the rod to support and prevent longitudinal movement of the controller, rotation of the latter sliding the abutment in one direction or the other to vary the tension of the spring.

5. In let-off mechanism for looms, a rocking carrier for the whip-roll, having an attached rocker-arm, a fixed guide, a rod longitudinally movable therein, a coupling connecting it with the rocker-arm, a sliding abutment on the rod, having a threaded hole, a tension-controlling spring surrounding the rod between the abutment and the guide, a rotatable controller mounted in the coupling and having a threaded end to engage the threaded hole in the abutment, and means to prevent longitudinal movement of the controller, rotation thereof moving the abutment to adjust the tension of the controller-spring.

6. In let-off mechanism for looms, a rocking carrier for the whip-roll, a tension-controlling spring for said carrier, means, including a movable abutment and an actuating device therefor, to adjust the tension of the spring, and a support for said means, operatively connected with the carrier.

7. In let-off mechanism for looms, a rocking carrier for the whip-roll, a tension-controlling spring for said carrier, means, including a movable abutment and a rotatable controller to move it and also to hold it in adjusted position, to regulate the tension of the spring, and a support for said means, operatively connected with the carrier.

In testimony whereof we have signed our names to this specification in the presence of two subscribing witnesses.

HENRY TOMLINSON.
JAMES J. MULDOWNEY.
